US0D1060210S

(12) **United States Design Patent** (10) Patent No.: **US D1,060,210 S**
(45) Date of Patent: ** Feb. 4, 2025

(54) **APPARATUS FOR SUPPLYING POWER**

(71) Applicant: **Instagrid GmbH**, Ludwigsburg (DE)

(72) Inventor: **Felix Fuchs**, Stuttgart (DE)

(73) Assignee: **INSTAGRID GMGH**, Ludwigsburg (DE)

(**) Term: **15 Years**

(21) Appl. No.: **29/812,004**

(22) Filed: **Oct. 19, 2021**

(30) **Foreign Application Priority Data**

Apr. 19, 2021 (WO) DM/214343

(51) LOC (15) Cl. **13-02**

(52) U.S. Cl.

USPC **D13/110**

(58) **Field of Classification Search**

USPC D13/110, 107, 103, 108, 106, 116, 119,
D13/152, 184

CPC Y02E 60/10

(57) **CLAIM**

The ornamental design for an apparatus for supplying power, as shown and described.

DESCRIPTION

FIG. 1 is a bottom view of an apparatus for supplying power, showing my new design;

FIG. 2 is a top view thereof;

FIG. 3 is a rear view thereof;

FIG. 4 is a front view thereof;

FIG. 5 is a side view thereof;

FIG. 6 is another side view thereof;

FIG. 7 is a front perspective view thereof; and,

FIG. 8 is a rear perspective view thereof.

Portions of the apparatus for supplying power shown in broken lines illustrate environment and form no part of the claimed design.

1 Claim, 8 Drawing Sheets
